ATTORNEY.

UNITED STATES PATENT OFFICE.

WILLIAM H. HART, JR., OF PHILADELPHIA, PENNSYLVANIA.

NECKTIE-SHIELD.

SPECIFICATION forming part of Letters Patent No. 235,527, dated December 14, 1880.

Application filed July 3, 1880. (No model.)

To all whom it may concern:

Be it known that I, WILLIAM H. HART, Jr., of the city and county of Philadelphia, and State of Pennsylvania, have invented a new and useful Improvement in Neckwear, which improvement is fully set forth in the following specification and accompanying drawings, in which—

Figures 1 and 2 are face views of neckscarfs embodying my invention. Fig. 3 is a view of the shield or support embodying my invention. Fig. 4 is a modification thereof. Fig. 5 is a section in line $\alpha\alpha$, Fig. 3. Figs. 6 and 7 are views of modifications.

Similar letters of reference indicate corresponding parts in the several figures.

My invention consists of a scarf shield or support formed of card-board, cloth-covered board, or other light material, retained in curved form by means of a strip or piece of rigid material, which likewise strengthens the shield, without, however, depriving it of its required or desired flexibility.

Referring to the drawings, A represents a necktie or scarf shield or support formed of card-board, cloth-covered paper, or other light and flexible material, as well known. B represents a transversely-extending strip of metal or other rigid material, of curved form, to correspond to the molded or curved form of the shield or scarf itself, and secured to the same, whereby, while the shield or scarf is of light and flexible material, it is sufficiently stiffened

and retains its curvature, as desirable, for imparting a proper fit to the scarf on the neck. 35

The strip may be secured to the shield by passing its ends through openings in the shield or bending the ends on the shield, or by riveting, sewing, gumming, or otherwise fastening the strip to the shield, and the strip 40 may be covered by the lining of the shield or a piece of card-board or other material attached to the shield.

Another advantage of the stiffening and retaining pieces is the adaptability of using 45 cheap stock for the shields or supports.

C represents the neckband of the scarf or tie, one end whereof is connected to the shield, and the other end is adapted to engage with the pin or clasp of the shield, as is well known. 50 To the band is secured a piece, D, of elastic material, which may be located at either end of the band, or between the ends thereof, so as to be continuous of the length of the band, forming, as it were, an expansible neckband. 55

Having thus described my invention, what I claim as new, and desire to secure by Letters Patent, is—

The neckwear-shield formed of flexible material, having a transversely-extending stiffening and retaining strip, B, of rigid material, substantially as and for the purpose set forth. 60

W. H. HART, JR.
